UNITED STATES PATENT OFFICE.

HENRY G. WILLARD, OF CHICAGO, ILLINOIS.

DESIGN FOR AN ELECTRIC-LIGHT FIXTURE.

SPECIFICATION forming part of Design No. 36,592, dated October 20, 1903.

Application filed May 6, 1903. Serial No. 155,949. Term of patent 7 years.

To all whom it may concern:

Be it known that I, HENRY G. WILLARD, a citizen of the United States, residing at Chicago, in the county of Cook and State of Illinois, have invented a new, original, and ornamental Design for Electric-Light Fixtures, of which the following, in connection with the accompanying drawings, is a full, clear, and exact specification.

In the said drawings, Figure 1 is a front elevation of an electric-light fixture embody-

ing my design, and Fig. 2 is a side elevation thereof.

What I claim as new therein, and desire to secure by Letters Patent, is—

The original and ornamental design for an electric-light fixture as shown.

HENRY G. WILLARD.
